J. C. CLARK.
PULVERIZING MILL.
APPLICATION FILED JUNE 27, 1913.

1,127,964.

Patented Feb. 9, 1915.

UNITED STATES PATENT OFFICE.

JOHN C. CLARK, OF ATLANTA, GEORGIA.

PULVERIZING-MILL.

1,127,964.

Specification of Letters Patent.

Patented Feb. 9, 1915.

Application filed June 27, 1913. Serial No. 776,193.

To all whom it may concern:

Be it known that I, JOHN C. CLARK, a citizen of the United States, and resident of Atlanta, Fulton county, State of Georgia, have invented certain new and useful Improvements in Pulverizing-Mills, of which the following is a specification.

This invention relates to pulverizing mills and more specifically to improvements in the mill shown in my prior Patent No. 1,049,051.

The objects of the invention are to provide a mill which is simple in construction and which is capable of developing a very powerful centrifugal crushing force.

Another object is to provide a mill in which the roll basin is stationary and surrounded by a suitable screen whereby the mill is adapted to deliver a finished product.

Another object is to provide a mill in which the springs for holding the pressure ring are arranged on the axis of the driving shaft so as to permit the use of very heavy springs and to avoid excessive compression of the springs due to the movements of the pressure ring.

Other objects and the features of novelty will be apparent from the following description taken in connection with the accompanying drawing which is a transverse section through a pulverizing mill embodying my invention.

Referring to the drawing, 10 indicates the usual basin which is supported on a suitable foundation and carries a track 11 for the balls 12 which do the crushing. As in the case of my prior Patent No. 1,049,051, I prefer to use three of the crushing balls 12, these balls being equally spaced by means of the spacing member 13 which is in the form of a flat plate provided with suitable recesses 14 in its periphery, to receive the balls, and rotatably arranged on a pin 15. The plate is supported by means of a thrust bearing 16 and carries on its under side wings or vanes 17 which act as a fan for the purpose of forcing the material out of the space below the plate 13.

Arranged above the balls 12 and resting thereon is a pressure ring 18 having arranged on the upper side thereof and in driving connection therewith a spider 19, the radial arms 20 of which carry at the center a cup 21. A frame work 22 is secured to the basin 10 and carries suitable bearings 23 and 24 for the driving shaft 25. A driving pul-

ley 26 is arranged on the shaft 25 and adapted to be connected therewith by means of a clutch 27 of any suitable construction, this clutch being operated to start or stop the shaft 25, by means of a hand lever 28. The basin 10 also carries a housing 29 for the pulverizing element, this housing having a top plate 30 so as to fully inclose the pulverizing elements. Arranged on the interior of the housing 29 and spaced therefrom is a suitable screen 31 which is adapted to screen the material and prevent the escape of all except that which has reached the requisite degree of fineness. The pulverized material passes through the screen 31 into the surrounding space 32 and is discharged through suitable openings 33 in the basin 10. It will be understood that suitable provision will be made below the mill for receiving the material which passes through the openings 33.

A vertical shaft 34 is supported in bearings 35 and 36, the bearing 35 being carried by the top plate 30, and the bearing 36 being carried by a suitable beam or cross member 36' which is adjustably supported on the frame work 22. A bevel gear 37 is splined on the shaft 34 and meshes with a pinion 38 on the driving shaft 25. The gear 37 is supported by a suitable ball thrust bearing 39, carried on the upper end of the bearing 35. The lower end of the shaft 34 carries a claw or clutch member 40 which engages the arms 20 of the spider 19 for the purpose of forming a universal driving connection between the spider and the shaft. A heavy compression spring 41 is arranged in the cup 21 and carries on its upper end a ball 42 which is arranged in a socket 43 in the lower end of the shaft 34. The shaft 34 has arranged on its upper end a ball thrust bearing 44 which carries a compression spring 45, the upper end of the shaft, the ball bearing and the spring being inclosed by a suitable casing or sleeve 46 secured to the cross beam 36'. Above the spring 45 is a plate 47 and a screw 48 which is provided with a hand wheel 49 which has threaded engagement with the top of the casing 46 and bears on the plate 47, for the purpose of adjusting the pressure which the spring 45 exerts on the shaft 34.

Any suitable means for feeding the material to be pulverized may be provided, and for this purpose I have shown somewhat

diagrammatically a hopper 50 from which a spout 51 delivers the material through the top plate 30 on to the spacing plate 13.

In the operation of the machine the shaft 34 is normally driven from the shaft 25 by means of the gears 37 and 38 and the motion of the shaft 34 is transmitted to the pressure ring 18 by means of the clutch member 40 and the spider 19. The pressure exerted by the spring 45 upon the upper end of the shaft 34 is transmitted through the ball and socket bearing 42 and the spring 41 to the spider 19, and from the latter to the pressure ring 18, thus pressing the balls 12 against the track 11. The rotation of the pressure ring 18 causes the balls 12 to revolve and travel around in the track 11, the normal surface speed of the balls being substantially the same as that of the surface of the pressure ring which contacts therewith and the revolution of the balls around in the track 11 being substantially one half the speed of rotation of the shaft 34. When the balls run onto a particle which lifts them the portion of the pressure ring immediately above the ball will be lifted the same amount and the center of the pressure ring will be lifted substantially one half of this amount. This motion of the pressure ring is distributed between the springs 41 and 45, each of the springs being compressed substantially one half of the movement of the cup 21, or one quarter of the amount of rise of the ball. The shaft 34 therefore is also raised one quarter of the amount which the ball is lifted. To accommodate this vertical movement of the shaft 34 the gear 37 is splined thereon and to accommodate the tilting of the pressure ring and spider the ball and socket bearing 42 is provided. The connection between the clutch 40 and the spider 19 also permits the tilting of the spider and the pressure ring.

The plate 13 maintains the balls in a definite spaced relation and revolves at substantially one half the speed of the shaft 34 so that the material delivered thereon by the spout 51 will be thrown, by centrifugal force, into the roll track 11, where it will be crushed by the balls 12. The dust or pulverized material rising from the track 11 passes through the screen 31 and is discharged through the openings 33, the screen also preventing the escape of the larger particles and returning them to the track 11.

From the foregoing description it will be apparent that in my improved construction the springs are moved only a very limited extent and therefore it is practical to em-

ploy very stiff springs and thus secure a heavy crushing force. By revolving the pressure ring the driving mechanism is much simplified and a very efficient and durable construction is provided. The pressure on the balls 12 can be varied by means of the screw 48 and the movement of the screw will be distributed between the springs 41 and 45, and thus equalize the tension of the springs.

While I have illustrated and described what I now believe to be the preferred form of my invention it will be understood that various changes may be made in the details of the construction within the scope of the claims and therefore I do not wish to be limited to the exact details shown and described.

Having thus described my invention, what I claim is:

1. In a pulverizing mill, the combination of a roll basin, a plurality of rolls arranged to run therein, a pressure ring, a rotatable and axially movable shaft, an axially arranged compression spring carried by the pressure ring, a ball and socket bearing between said spring and one end of said shaft, a driving connection between said shaft and the pressure ring permitting the ring to be tilted relative to the shaft and a compression spring at the opposite end of said shaft and opposing said first mentioned spring.

2. In a pulverizing mill, the combination of a roll basin, a plurality of rolls arranged to run therein, a pressure ring, a rotatable and axially movable shaft, a yieldable driving connection between said shaft and said pressure ring, a compression spring at the outer end of said shaft and adapted to yieldingly force the pressure ring against the rolls, and a driving wheel held against axial movement and having a slidable connection with said shaft.

3. In a pulverizing mill, the combination of a horizontally arranged roll basin, a plurality of rolls arranged to run therein, a pressure ring engaging the top of said rolls, a vertical driving shaft, a yielding connection between said shaft and said pressure ring, a compression spring at the top of said shaft, means for varying the tension of said spring, and a horizontally arranged driving wheel for said shaft held against axial movement and having a sliding connection therewith.

In testimony whereof I affix my signature in presence of two witnesses.

JOHN C. CLARK.
